SUPPORTING STAND FOR GYMNASTIC VAULTING BUCK

George P. Nissen and Lawrence H. Conover, Cedar
Rapids, Iowa, assignors to Nissen Corporation, Cedar
Rapids, Iowa

Filed Nov. 1, 1961, Ser. No. 67,341

Term of patent 14 years

(Cl. D34—5)

FIGURE 1 is a perspective view of the supporting stand for a vaulting buck embodying our new design;
FIGURE 2 is a top plan view of the apparatus; and
FIGURE 3 is a side elevational view of the apparatus.
The broken line showing of a vaulting buck is for illustrative purposes only.

We claim:

The ornamental design for the supporting stand for gymnastic vaulting buck, as shown and described.
